APPARATUS FOR ELECTROSTATIC ATOMIZATION

Edwin M. Ransburg and Emery P. Miller, Indianapolis, Ind., assignors to Ransburg Electro Coating Corp., Indianapolis, Ind., a corporation of Indiana

Application April 14, 1950, Serial No. 155,802

14 Claims. (Cl. 118—51)

This invention relates to a new and improved apparatus for electrostatically atomizing liquid materials and to an apparatus adapted for use in the application of liquid coating materials with electrostatic forces. More specifically the invention resides in an electrostatic atomizing apparatus in which the source of the atomized particles is linearly extended to produce an elongated spray pattern of atomized particles.

One object of the invention is to counteract or compensate for the tendency of gravity to cause an uneven distribution of liquid along an inclined or vertically disposed discharge member from which the liquid is to be atomized.

Another object of the invention is to provide a more uniform extended source of atomized liquid material by providing an apparatus through which a uniform extended liquid film can be obtained upon an appropriate discharge surface.

A further object of the invention is to provide an extended continuous source of atomized material which can be adjusted to give uniformity along its length regardless of its angle to the horizontal and of the flow characteristics of the material being atomized.

Still another object is to provide an improved feeding means for effecting a uniform distribution of liquid to the extended discharge member of an electrostatic atomizer.

A principal feature of the invention is the provision in an electrostatic atomizer of a movable discharge member which wipes past a stationary shielding member and is partially shielded thereby at the site of atomization. In the preferred form of the invention, the liquid to be atomized is distributed along the shielding member and transferred therefrom to the discharge member, distribution of the liquid to the discharge member being accomplished with the aid of a rotating distributor which discharges liquid progressively to points distributed along the shielding member.

The above and further objects of the invention will be apparent from the following description and figures:

Fig. 1 is a partially sectioned isometric of the apparatus of the invention as arranged to atomize material which is then to be precipitated as a protective coating upon articles of manufacture;

Fig. 2 is a sectional view showing a modification of the apparatus;

Fig. 3 is an isometric drawing of the liquid supply means to be used with the atomizer of Fig. 1;

Fig. 4 is a diagrammatic development showing the arrangement of the ports in the rotary plug of the atomizer to be used with the bellows-type pump;

Fig. 5 is a diagrammatic development of another arrangement of ports for the atomizer to be used with a constant delivery pump.

As shown in Fig. 1 the apparatus as arranged to coat articles consists of an atomizer shown generally at 1 positioned opposite to and spaced from a series of holders 2 upon which the articles to be coated 3 are held. The holders are preferably arranged on a conveyor so that the articles can be moved successively past the atomizer. The atomizer is oriented with respect to the articles in such a way that the movable elongated discharge member 4 of the head is nearest the articles and extends approximately parallel to the surface to be coated.

A high-voltage source 5 has one of its terminals 6 connected to said head and hence to the discharge mem-

ber. The other terminal 7 is grounded. Since the conveyor is grounded as at 8 the articles to be coated are likewise grounded by way of the holders 2. An electrostatic field is thus maintained between the discharge member and the article surface. Due to the character of the discharge member and the separation between it and the article to be coated the field adjacent the member is one of steep potential gradient. Liquid material on the discharge member thus finds itself in this field, and by it is formed into a series of liquid cusps based upon the discharge member and extending outward from it toward the article. In Fig. 1 these cusps drawn solely for the purposes of illustration are shown for a short portion only of the lower section of the discharge member. From the apexes of these cusps atomized material is projected into the space in front of the member and by the field is precipitated on the article.

To supply coating material to the discharge surface in a uniform and consistent manner so that the cusps formed will be stable, the atomizer is composed primarily of body member 9 that is drilled and reamed to accept a cylindrical plug 10 having through it a series of diametrical holes 11. These holes are spaced lengthwise of the plug at equal spacings corresponding to a similar set of holes 12 in the body of the atomizer. Starting at one end of the plug the holes 11 are spirally placed about the circumference of the plug in such a way that the separation of their centers at the plug surface is equal to at least twice their bore. This spacing is continued until the spiral on which the holes lies extends one-half the distance about the circumference of the plug. This length of the plug is herein referred to as a section. The spiral of holes is continued downward along the plug until its entire length is drilled to form a given number of complete sections.

Diametrically opposite and across the plug from the holes 12 is a longitudinally extending port 13 which is separated into lengths by a series of walls in the port formed by the screws 14 of Fig. 1 and 114 of Fig. 2. These screws are threaded into holes in the body 9 before the hole which receives plug 10 is drilled and after the hole 13 is drilled. In this manner a tight fit to plug 10 is obtained and separation of port 13 into lengths is guaranteed. These lengths correspond to the length of a section on the plug as referred to above. Each section of the port 13 is connected externally by means of a connection 15 and a tube 16 to a bellows-type pump 17 whose inlet orifice 18 is connected to a source of liquid to be atomized. A common source of material may be employed to feed all the pumps for the various sections of the atomizer. These pumps and their drives are more fully explained and shown in connection with Fig. 3.

The holes 12 exit onto an exposed surface 19 of the body of the atomizer. Extending across this surface and sloping generally downward are a series of flow-directing elements 20. Each of orifices 12 terminates on the surface 19 between two such elements.

The extreme forward edge of the body member 9 is grooved to accept the discharge member 4. This discharge member during operation moves parallel to its length in this groove and over the two end castings in a continuous loop. A top casting 21 is formed to seal off the upper end of the hole carrying plug 10. A similar bottom casting 22 seals off the lower end of this same hole and provides a bearing and packing gland for the end extension 23 of the plug 10. This end extension 23 serves as a drive shaft by which the plug 10 can be rotated with respect to body member 9. Rotation is accomplished by a flexible shaft extending from shaft extension 23 of Fig. 1 to the connection 223 shown in Fig. 3. The top end casting 21 has built into it two rollers bearing on pins 24. These two rollers serve to guide the discharge member 4 as it passes over the top of the atomizer. A groove 25 may be provided to accept the discharge member as it moves along the rear of the atomizer body. At the bottom casting two more rollers one pinned on pin 26 and another keyed to shaft 27 guide the discharge member as it returns to travel upward along the groove in the forward part of the body casting. Between the two rollers on the top casting the

3

discharge member passes through a cleaning member 28 which is arranged to wipe the remaining liquid from the discharge member and collect it in a catch basin for return to the supply by way of pipe 29. Between the two rolls on the bottom casting the discharge member passes by two additional cleaning members 30 and 31 arranged with catch pans that feed the reclaimed material to the supply by way of pipe 32. These cleaning devices 30 and 31 are supported by brackets extending from the lower casting 22.

The roller which is keyed to shaft 27 and over which discharge member 4 passes is rotated by worm 33 and worm gear 34. Worm 33 in turn is rotated by flexible shaft 35 which also is shown in Fig. 3. The discharge member will thus be moved progressively along the forward part of the body member, across the upper end, past the cleaner 28, down the rear of body member, and across the lower end. The speed of travel of the discharge member is thus independent of rotation of plug 10 and adjustable by speed control 237 shown in Fig. 3.

Located along the back of body member 9 is an idler wheel 36 which is mounted on springs 37. This idler is arranged to maintain tension on the discharge member 4 as it travels down the groove 25 in the back of body member 9.

Fig. 3 shows the fluid supply and drive mechanism used in conjunction with the atomizer shown in Fig. 1. In this figure a motor 236 drives the speed reducer 237 having two output speed drives 238 and 239. Drive 238 rotates at a constant speed while drive 239 is variable under control of knob 240. Drive 239 by a flexible shaft is connected to shaft 35 of Fig. 1 and thus drives discharge member 4. Drive 238 drives shaft 241 on discharge member 4. Drive 238 drives shaft 241 on which are positioned gear 242 and cams 243. Meshed with gear 242 is gear 244 and gear box 252 that drives flexible shaft 223 which in turn is connected to shaft 23 of Fig. 1 and thus is used to rotate plug 10. Cams 243 are arranged to activate pins 245 that move the bellows-pumps 17. Motion of these pumps transfers material from supply tank 247 by way of base reservoir 248 to outlet pipes 16. Part 250 is in engagement with grooves on shaft 241 and thus maintains its endwise position. By loosening 250 shaft 241 can be moved endwise to engage a different group of cams 243 with pins 245. The strokes of the bellows-pumps are thus modified and the fluid per stroke delivered to each section of atomizer 1 is therefore altered. Pipes 29 and 32 of Fig. 1 are connected to pipe 251 on fluid supply tank so coating material removed from the discharge member 4 by scrapers 28, 30 and 31 is returned to the reservoir.

Fig. 4 illustrates by a plane development of the surface of plug 10 the relationship of the holes 11 and the holes 12 in the body 9. The circles marked I, II and III in line A are representative of holes 12 in the body 9 while those marked IV, V and VI represent the holes 11 about the circumference of the plug so that a circumferential distance equal to their diameter exists between them. The relationship which exists between the moving and fixed orifices can be simulated by passing lines (a) and (b) (c) (d) (e) etc. in succession over line A. When (b) coincides with line A hole IV is connected to hole I and remains so as (b) and (c) are in turn brought over line A. When (d) coincides with A no connection between holes is established. As (e), (f) and (g) in turn pass over line A, hole II is connected to hole V. It is thus evident that only one hole at a time is connected in any section. With this arrangement the particular pump supplying the section is coordinated with the rotation of plug 10 so that the pump moves upward on intake when (c), (d) and (e) successively coincide with A and moves downward to deliver fluid as (e), (f) and (g) move into coincidence with A. Gearing in gear box 252 permits this coordination between pumps and the rotation of plug 10.

In operation the following sequence takes place, the drive motor 236 rotates shaft 23 and operates pumps 17 in timed relation. Material to be atomized is therefore brought from the supply 247 by each pump 17 and introduced into the corresponding section of port 13. The rotation of plug 10 as above described is so timed with the motion of the bellows of pump 17 that fluid will be delivered to the port 13 only when one of holes 11 in the particular section is open to its corresponding orifice 12. In this way positive delivery is assured and

plugging of delivery tubes will be reduced to a minimum. As the rotation of the plug 10 continues material will be delivered progressively along each section of the blade as each hole in the plug is matched with its corresponding orifice 12 and the particular pump strokes to deliver the appropriate fluid quantity. Fluid is thus delivered progressively onto the surface 19 between successive pairs of the flow-directing elements 20. The quantity of fluid delivered to each orifice 12 can be controlled as above mentioned by regulating the stroke of the pump.

The liquid delivered to the flow surface 19 moves over this surface to the forward edge thereof where it is delivered to discharge member 4. On this surface the material is formed by the electrostatic field into cusps which tend to be carried along with the discharge member as it moves upward. Additional material is fed to these cusps from that flowing across surface 19 while material is being atomized from the apexes of the cusps into the space adjacent the discharge member for precipitation upon the article. Because gravity would normally cause the cusps to move downward along the discharge member it is evident that by regulating the rate of linear motion of the discharge member by controlling knob 240 the cusps can be made to move upward, downward or remain at rest as desired.

By this construction one can fully utilize the known advantages of a fine smooth cylindrical surface as a discharge member. By backing such a member with a shielding member such as body member 9 the tendency of such cylindrical surfaces to discharge into the entire area about them is confined and restricted to that area which is unshielded. A directional effect can thus be obtained. Whereas, complete electrical shielding of the rear section of the discharge edge is preferably obtained with a metal body member 9, such body members may be of insulating material. The discharge member likewise can be of insulating material if the liquid material has sufficient electrical conductivity to allow one to establish at its exposed surface the necessary electrical potential gradient.

Whereas the arrangement shown in Fig. 1 illustrates the invention being used to coat articles of manufacture it is to be understood that the operation described can be used for any purpose wherein one desires to produce a dispersion of finely divided liquid particles. The object being coated is not an essential part of the function of the device. Such a device will atomize liquid material into the space about the discharge member quite readily if it is placed alone in the center of a room. One only needs to establish adjacent the liquid on the discharge member a sufficient potential gradient and atomization will result.

Whereas the atomizer shown in Fig. 1 embodies the delivery of the liquid material from the distributing means 19 to orifices 12 and then onto an exposed surface 19 across which it flows to the surface of the discharge member, the arrangement shown in Fig. 2 is equally operable. In this modification of the invention the material from port section 113 flows through holes 111 in plug body 110 and into orifices 112. In this modification the orifices 112 terminate not on a free surface, but at the base of groove 115 cut in the forward part of body member 109 to receive discharge member 104. Material from orifices 112 then flows around wire 104 to the exposed surface thereof to be atomized therefrom.

By rearranging the holes 11 in the plug it is possible to use in place of the bellows-pumps 17 a series of gear-type pumps which deliver fluid at a constant rate. This arrangement of holes is shown in development in Fig. 5 where the circles VII, VIII and IX represent holes 11 spaced apart about the circumference of the plug by a distance equal to their radius. It will be evident that as (m) and (n) are moved over line A port I will be connected to port VII and that as (o) and A coincide port I will lose connection with port VII and port II connects with port VIII. The sequence of connection is thus one of alternate connection to single and double ports. It is thus evident that this arrangement permits the use of a constant flow pump because it is never shut completely off but is connected alternately to one orifice alone and then to two adjacent orifices. Plugging of orifices is equally avoided by this arrangement.

From the above description the method of operation of the invention is evident. It is understood that the

method described is only one possible arrangement and others may be employed without departing from the spirit of the invention.

What we claim is:

1. In an apparatus for applying material to the surface of an article, a support for the article to be coated, an extended discharge member positioned in spaced relation to the article on said support, a surface shielding member adjacent and extending along said discharge member on that side thereof which is remote from the article, means for creating relative movement between said shielding member and said discharge member in the direction in which said discharge member extends, feed means for supplying material to that surface of said discharge member which faces the article and high-voltage means to establish adjacent the material on said discharge member a potential gradient to transfer said material from said discharge member to said article surface, said motion producing means being power driven and operative during the material transfer operation.

2. In apparatus for atomizing liquid, an elongated discharge, a distributing means comprising a rotary multi-ported valve for distributing liquid progressively along said discharge member, means for effecting relative movement between said discharge member and said valve in a plurality of directions, and means for atomizing liquid from said member.

3. In apparatus for atomizing liquid, an elongated discharge member, an imperforate shielding member disposed adjacent said discharge member for shielding one portion thereof and leaving another portion exposed to the atmosphere, means for causing relative movement between said discharge member and said shielding member in the direction of elongation of said discharge member, and means for supplying liquid coating material to the exposed portion of said discharge member for atomization therefrom.

4. Liquid atomizing apparatus comprising a discharge member with an elongated continuous discharge surface, means including an elongated rotary member arranged generally parallel to said elongated discharge surface for distribution of liquid to it, means for effecting relative movement between said discharge member and said elongated rotary member in the direction of elongation of said members, and means for atomizing the liquid from said elongated discharge surface.

5. In an atomizer, an extended discharge member, an elongated shielding member adjacent said discharge member and extending parallel to the discharge member along one side thereof to leave a portion of the discharge member exposed, means for producing relative motion of said discharge member and said shielding member along a path generally parallel to the extent of said discharge member, means for supplying liquid to said exposed portion for atomization therefrom, and a high voltage source connected to said discharge member for establishing the liquid on said exposed portion as one terminal of an electrostatic field for influencing the paths of the atomized particles leaving said liquid, said motion producing means being power-driven and operative during the atomization operation.

6. The invention claimed in claim 5 with the addition that the liquid to be atomized is fed to an exposed surface of said shielding member for flow thereover to said discharge member.

7. The invention claimed in claim 6 with the addition of a series of flow-directing elements on said exposed surface of said shielding member and disposed at an angle to the direction of extent of said discharge member.

8. In an atomizer, an extended discharge member, an elongated shielding member adjacent said discharge member and extending parallel to the discharge member at one side thereof to electrically shield a portion of said discharge member, means for producing relative motion of said discharge member and said shielding member along a path generally parallel to the extent of said discharge member, means for supplying liquid to said unshielded portion for atomization therefrom, and a high voltage means connected to said discharge member for establishing the liquid on said unshielded portion as one terminal of an electrostatic field for influencing the paths of the atomized particles leaving said liquid, said motion

producing means being power-driven and operative during the atomizing operation.

9. In an electrostatic coating apparatus; a device for atomizing liquid, said device comprising an extended discharge member having first and second portions, means for moving said discharge member in the direction of its extent, means for supplying liquid to said first portion for atomization therefrom, and a member for shielding said second portion; means for supporting an article to be coated in opposed spaced relation to said first portion; and a high voltage source for establishing an electrostatic field between the liquid on said first portion and the supported article for electrostatically depositing on the article as a finished coating the atomized material emanating from the liquid on said first portion.

10. The invention claimed in claim 9 with the addition that the feed means is arranged to flow material onto said shielding means for flow thereover to said first portion.

11. In an atomizer, a discharge member having an extended edge, means for supplying liquid to said extended edge for atomization therefrom in the form of a spray, a high voltage source connected to said discharge member as one terminal of an electrostatic field for influencing the paths of the spray particles leaving said liquid, and electrical shielding means adjacent said discharge member for modifying the pattern of the spray emanating from the liquid on said discharge edge, and a power operated means for producing relative motion during the atomizing operation of said discharge member and said shielding means along a path generally parallel to said extended edge.

12. In an atomizer, an extended discharge member mounted for movement in a direction parallel to its extent, means for moving said discharge member, an elongated shielded member adjacent said discharge member and extending parallel to the discharge member along one side thereof to shield a portion of said discharge member as it moves past said shielding member, means for supplying liquid material to the unshielded portion of said discharge member for atomization therefrom, said supply means comprising a fluid pump and a multiple ported rotary valve system, said pump being synchronized with said valve system so that material is delivered from only one port at a time, and a high voltage source connected to said discharge member for establishing the liquid on said unshielded portion as one terminal of an electrostatic field for influencing the paths of the atomized particles leaving said liquid.

13. In an atomizer, an extended discharge member mounted for movement in a direction parallel to its extent, means for moving said discharge member, an elongated shielded member adjacent said discharge member and extending parallel to the discharge member along one side thereof to shield a portion of said discharge member as it moves past said shielding member, means for supplying liquid material to the unshielded portion of said discharge member for atomization therefrom, a high voltage source connected to said discharge member for establishing the liquid on said unshielded portion as one terminal of an electrostatic field for influencing the paths of the atomized particles leaving said liquid, and a scraping cleaner located along the path of movement of said discharge member to remove excess remaining material from said discharge member.

14. The invention claimed in claim 11 with the addition that said power operated means is connected to said discharge member to produce said relative motion, and means for maintaining said shielding member at an electrical potential of the same sign as said discharge member.
